A 1951 U.S. Patent for a "Machine for folding strip into tubes or sections" is shown. The patent is assigned to Joshua Bigwood & Son, Limited, of Wolverhampton, England. The application was filed on February 25, 1948, with a serial number of 10,638. The patent was granted on July 24, 1951, with a patent number of 2,561,634.

UNITED STATES PATENT OFFICE

2,561,634

MACHINE FOR FOLDING STRIP INTO TUBES OR SECTIONS

John Burley Picton, Wolverhampton, England, assignor to Joshua Bigwood & Son, Limited, Wolverhampton, England

Application February 25, 1948, Serial No. 10,638
In Great Britain February 26, 1947

3 Claims. (Cl. 153—54)

1. A machine for folding strip into tubes or sections, comprising:

This invention relates to machines of the kind wherein a length of strip, usually metal, is moved endwise and acted upon at spaced positions along its length by a number of rolls, usually arranged in pairs, which rolls fold the strip as it passes through the machine in a series of successive steps into the required tubular form, or into the required sectional shape. In such machines the cross-sectional shape of the strip at various positions along its length varies from the original section, which is usually flat, through a series of partly folded sections, to the final section, which may be that of a circular tube.

The object of the present invention is to provide an improved construction.

According to the present invention the machine comprises a bed upon which are mounted a plurality of units each incorporating one or more driven folding rolls for acting upon the strip to effect the necessary folding thereof, the units being disposed in alignment and engaging unit-guiding means on the bed, and being movable along such guiding means so that their spacing can be adjusted, means being provided for retaining them in any desired adjusted position.

The machine may incorporate a driving shaft arranged parallel to the row of folding units, and each such unit may incorporate a fixed housing containing transmission gear for transmitting the drive from a gear element driven by and adjustable along the driving shaft to the shafts of the folding rolls.

The driving shaft may be supported by bearings, one adjacent to each gear element, and these bearings may slide on a bearing guide on the bed of the machine so that adjustment in the spacing of the folding units can be effected.

Each unit may comprise a base having a fixed housing containing the driving transmission means for the shafts for the pair of rolls and supporting one end of a pair of roll shafts, this base being slidable on the guide on the bed and the guide being parallel to the pass, each unit base having a guide which is at right angles to the pass, and mounted on this guide is a loose bearing for the other ends of the roll shafts, the arrangement being such that the loose bearings are adjustable parallel to the roll shafts so that the span between the roll shaft bearings can be adjusted to suit the load on the shaft and the length of the rolls.

The roll shafts of the units may be arranged one above another, and one of these roll shafts is preferably capable of being adjusted towards and away from the other.

2. A machine for folding strip into tubes or sections, comprising:

Referring to the drawings:

Figure 1 is a view in side elevation;

Figure 2 is a plan view;

Figure 3 is a section on the line 3—3 of Figure 2, and

Figure 4 is a section on the line 4—4 of Figure 2.

In the construction shown in the drawings the machine comprises a bed 10, which is of hollow box-like form, and on the top of this bed the surface is provided with two guide ribs 11 and 12 which are parallel to each other. These guides are formed by upwardly-projecting rectangular-section ribs on the surface of the bed top.

15. Mounted on the guide 12 are a number of, say six, units 13, three of which can be seen in Figures 1 and 2, each unit being adjustable along the guide and being secured to a base plate 16 having longitudinal slots 14 through which extend upwardly-projecting studs 15 on the bed 10, so that the plates 16 can be individually adjusted along the bed to allow the spacing of the units to be adjusted, and the plates 16 can be locked to the base by the studs 15 in the required positions 25 and at the desired spacing.

Each of the units 13 includes a fixed housing 17 providing bearings for upper and lower roll shafts, and a loose housing 18 also providing bearings for upper and lower roll shafts.

Each of the plates 16 is provided with an upwardly-projecting rib 19 on its upper surface, and the members 17 and 18 are located on the rib 19. The member 17 may be suitably secured by bolts or other fastenings to the plate 16, and the plates 16 are provided with slots 20 which are parallel to the rib 19 for receiving fastenings 21 by which each loose housing 18 is secured to the plate 16, the arrangement being such that the loose housing can be adjusted towards and away from the fixed housing 17 and then secured in any desired adjusted position.

Each of the fixed housings 17 is of hollow box-like form and comprises a front wall 22 and a rear wall 23. Bearing housings 24 and 25 are formed in the walls 22 and 23, these housings containing bearings 26 and 27 in which the lower roll shaft 28 can rotate.

At a higher level the front wall 22 has formed on its rear surface vertical guides 29 within which can slide an upper bearing housing 30 containing bearings 31, 32 in which the upper roll shaft 33 is mounted for rotation. The guides 29 are vertical, and they are connected to the side walls of the housing by webs 34, 35. The lower parts of the side walls are shown at 36, 37.

Each bearing housing 30 is provided with two portions 38 which engage the edges of the guides 29. Each of the bearing housings 30 can be raised and lowered by a screwed stem 40 engaging a sleeve nut 41, which is mounted in the top plate 42 of the housing, the sleeve nut 41 being provided with a head 43 which can be turned by hand and locked by a nut 44. The stem 40 is provided with a circumferential groove 45 engaged by a plate 46 on the upper side of the bearing housing 30, and below the plate 46 in a recess in the top of the bearing housing is a head 47 on the stem 40. With this arrangement when the sleeve nut 41 is turned by turning the head 43 the bearing housing 30 is raised or lowered.

The loose housing 18 is also provided with a lower bearing 48 which does not move and an upper bearing 49 which can be raised and lowered by means (shown in Figure 3) which are exactly similar to the means shown for raising and lowering the bearing housing 30.

With the arrangement described the upper roll shaft 33 can be raised when required, and the distance between the rolls can be altered to suit the work, which is indicated at 50. Further, the loose housing 18 can be adjusted towards or away from the fixed housing 17 so that different lengths of roll may be accommodated.

Returning to the fixed housing 17, the upper rear part of the housing is formed by a cover 51 secured to the rear wall 23 and to the top plate 42. The front part of the fixed housing 17 is provided with a removable cover 52.

Both the roll shafts are positively driven and they are geared together by means which remain in effective driving engagement whatever may be the position of the upper roll shaft.

The housing 17 provides a bearing in its wall 22 for a shaft, the end of which can be seen at 53, and mounted on this shaft 53 is a pair of links 54 which are pivoted at 55 to another pair of links 56 pivotally mounted on the end of the upper roll shaft 33.

A gearwheel 57 is provided on the lower roll shaft 28, and this gearwheel 57 gears with a gearwheel 58 on the shaft 53. The gearwheel 58 engages with a gearwheel 59 on the pivot pin 55, and the gearwheel 59 engages with a gearwheel 60 on the upper roll shaft 33. If the upper roll shaft 33 is raised or lowered by raising or lowering the bearing housings 30, 49, then the links 56 and 54 can oscillate to permit of the required movement of the bearing housings without interrupting the drive. It will be seen that the roll shafts 28 and 33 are driven in opposite directions and at the same speed.

An upper roll is indicated at 61 and a lower roll at 62. These rolls have portions which are shaped to bend the work 50 into channel section. Rolls of different peripheral forms will be provided on the roll shafts of successive units, and the rolls may be shaped so as to convert a flat strip gradually in a series of steps into any required section. In one arrangement the rolls may convert a flat strip by a series of steps into a circular-section tube.

Motion is imparted to the lower roll shaft 28 from a driving shaft 63 driven through a clutch 64 from a pulley 65 coupled by belts or the like to a pulley 66 on the driving shaft 67 of a power unit 68, such as an electric motor.

The driving shaft 63 is arranged parallel to the row of units, and at intervals it is provided with bearings 69 and with driving gearwheels 70.

Each of the bearings 69 is formed on a bracket

71 which is slidably mounted on the guide rib 11 on the bed 10. Each of the brackets 71 can be retained in any desired position along the length of the shaft 63 and it is understood that when one of the units is adjusted parallel to the shaft 63 the bracket 71 carrying the bearing 69 and gearwheel 70 is adjusted along the shaft with the unit, so that the gearwheel 70 always remains in effective driving engagement with a gearwheel 72 mounted on a worm shaft 73 supported in bearings 74, mounted in the bearing housings 75 in the housing.

The wall 31 of the housing is formed to provide a pocket 76 for the gearwheel 72 so that the gearwheel is disposed within the boundary of the sides of the housing. With this arrangement the housings can be adjusted parallel to the work part to provide the minimum spacing between successive pairs of rolls.

Means are preferably provided for releasably securing the brackets 71 in any adjusted position.

The worm shaft 73 is provided with a worm 77 which engages with a worm wheel 78 on the lower roll shaft 28 so that the latter is driven through the worm gearing and through the gears 72 from the driving shaft 63.

Each of the units may be provided with a work-supporting bracket 79 for supporting the work between the pairs of rollers. Each of these brackets may be supported upon legs 80 secured to the plate 16.

The end of the driving shaft 63 is supported in a bearing 81, which may either be fixed or slidably mounted on the rib 11.

The unit 82 at the end of the row may be of special construction in which the screws 40 for raising and lowering the bearing housings 30 and 49 are simultaneously operable by turning a hand wheel 83 on a shaft 84 at the top of the loose housing, this shaft 84 being coupled by worm gearing to the sleeve 41, and further the shaft 84 may be connected by a detachable coupling 85 to a shaft 86 which drives the worm gearing at the top of the stationary housing for driving the sleeve 41 therein.

Further, the lower bearings 26 and 48 in this construction may be mounted in bearing housings 87, which are similar to the bearing housings 30 and can be raised and lowered in the guides 29, these bearing housings being operated by turning a hand wheel 88 on a shaft 89 mounted in brackets 90 and operating, through worm gearing, threaded sleeves 91 upon fixed screws 92 so that the lower roll shaft 28 may be raised and lowered. The shaft 89 may incorporate a detachable coupling permitting the loose housing 18 to be moved towards or away from the fixed housing 17.

The invention thus provides a means whereby the spacing between individual forming units, each incorporating a pair of driven rolls, can be adjusted to suit different thicknesses, dimensions and qualities of metal so as to ensure that the metal is not overstressed between any two folding operations, and to ensure that the stretching of the edge of the metal is kept down to the minimum.

Further, the ability to adjust the folding units towards and away from one another permits of the insertion of power-driven guide rolls, which may be on axes which are transverse to the axes of the forming rolls. Such guide rolls can be inserted between the folding units when desired. Further, the improved construction per-

mits any individual folding units to be removed without interrupting the drive to the others, and such units can be replaced on the guide provided on the bed in the minimum of setting-up time.

Further, the loose bearing housings, one on each folding unit, permits of the span between the bearings of the roll shafts to be adjusted to suit the load and the particular roll used. Such loose bearing housings can be adjusted and fixed with the minimum of difficulty.

Further, the driving shaft of the machine is adequately supported in bearings, one adjacent each folding unit, and these bearings can be adjusted along the guide on the bed and in no way interfere with the correct and variable spacing of the gear elements which drive the unit.

What I claim then is:

1. A machine for folding strip into tubes or sections comprising a machine bed, a primary guide on said bed, a plurality of strip folding units mounted in alignment on said bed, each of said units engaging said primary guide, said units being movable on said primary guide, means for locking said units to the bed in any selected adjusted position, each unit comprising a housing containing transmission gear for driving the shafts of a pair of folding rolls, said transmission gear including a shaft projecting through a side wall of the housing, a gearwheel on said projecting part of said shaft, a bearing guide on said bed, said primary and bearing guides being parallel, a driving shaft arranged parallel to the row of units bearings for said driving shaft fixed on the machine bed, and brackets slidably mounted on said bearing guide, said brackets each having a bearing for the driving shaft and carrying a gear element driven by said driving shaft, each of said gearwheels being engaged and driven by one of the gear elements on said driving shaft.

2. A machine for folding strip into tubes or sections comprising a machine bed, a primary guide on said bed, a plurality of base plates movably mounted in alignment on said bed, each of said base plates engaging said primary guide, locking means engaging each of said base plates and the bed for locking said base plates to the bed in various positions whereby the spacing of said base plates can be adjusted, a strip folding unit on each of said base plates, each unit comprising a housing containing transmission gear for driving the shafts of a pair of folding rolls, said transmission gear including a shaft projecting through a side wall of the housing, a gearwheel on said projecting part of said shaft, a bearing guide on said bed, said primary and

bearing guides being parallel, a driving shaft arranged parallel to the row of units bearings for said driving shaft fixed on the machine bed, and brackets slidably mounted on said bearing guide, said brackets each having a bearing for the driving shaft and carrying a gear element driven by said driving shaft, each of said gearwheels being engaged and driven by one of the gear elements on said driving shaft.

3. A machine for folding strip into tubes or sections comprising a machine bed, a primary guide on said bed, a plurality of base plates movably mounted in alignment on said bed, each of said base plates engaging said primary guide, locking means engaging each of said base plates and the bed for locking said base plates to the bed in various positions whereby the spacing of said base plates can be adjusted, a strip folding unit on each of said base plates, each unit comprising a fixed housing containing transmission gear for driving the shafts of a pair of rolls, and a loose housing, a secondary guide on said base plate disposed at right angles to said primary guide, guide means on said loose housing engaging said secondary guide and means for locking said loose housing to said plate in various positions thereon, whereby the spacing of said housings can be adjusted to accommodate roll shafts of varying lengths, a shaft protruding through the side wall of said fixed housing and drivingly connected with said transmission gear, a gear wheel on said projecting part of said shaft, a bearing guide on the machine bed, the primary and bearing guides being parallel, a driving shaft arranged parallel to the row of units, bearings for said driving shaft fixed on the machine bed and brackets slidably mounted on said bearing guide, said brackets each having a bearing for the driving shaft and carrying a gear element driven by said driving shaft, each of said gear wheels being engaged and driven by one of the gear elements on said driving shaft.

JOHN BURLEY PICTON.
